UNITED STATES PATENT OFFICE.

SAMUEL HERMANN, OF CINCINNATI, OHIO.

SHOE-RACK.

940,812.

Specification of Letters Patent. Patented Nov. 23, 1909.

Application filed April 27, 1908. Serial No. 429,523.

To all whom it may concern:

Be it known that I, SAMUEL HERMANN, a citizen of the United States of America, and resident of Cincinnati, county of Hamilton, 5 State of Ohio, have invented certain new and useful Improvements in Shoe-Racks, of which the following is a specification.

The object of my invention is a shoe rack, which is durable and convenient for supporting shoes in various positions.

Referring to the accompanying drawings, in which like parts are indicated by similar reference letters, Figure 1 is an end view of a shoe rack embodying my invention. Fig. 15 2 is an end view of one of the cross rods and a shoe support, upon an enlarged scale. Fig. 3 is a perspective view of the parts illustrated in Fig. 2. Fig. 4 is a view of the cross-rod and of a modified form of the 20 support upon line v — x Fig. 5. Fig. 5 is a perspective view of the parts shown in Fig. 4.

The rack consists of end frames, A, cross- rods, B, and a series of shoe supports, C, mounted upon the cross-rods, B. The end 25 frames are made preferably of vertical tubes connected by horizontal rods, a , a' , and of intermediate bolts, a^2 , which pass through the standards. The cross-rods consist of two metal bars, b , b' , between which the bolts, a^2 , 30 of the end frames are grasped, the bars being held together by screws, b^2 . The series of cross-rods are staggered, as shown in Fig. 1.

Each of the series of shoe supports of the 35 form shown in Figs. 1 through 3, consists of a wire bent into three loops, c , c' , and c^2 . The central loop, c' , has parallel sides. The loops, c , and c^2 , have bends, c^3 and c^4 in them so as to form sockets, c^5 and c^6 with 40 the sides of the loop, c' , and so as to form sockets in the outer ends of each loop. Loops, c , and c^2 , have their outer sides bent upward into lugs, c^7 and c^8 . The inner bends, c^9 and c^{10} , of the wires pass around 45 screws, b^3 and b^4 of the cross rods and the ends of the wires stand adjacent to screws, b^2 and b^5 in the cross rods. Each support, C, is inclined upward from the cross rod.

In use a pair of shoes may be supported in an inverted position upon each support, by 50 passing the tops between the loop, c , and the loop, c' , and between the loop, c' and the loop, c^2 so as to bring the tops into the sockets, c^5 , and c^6 , respectively. In this position the lugs, c^7 and c^8 , contacting the 55 vamps of the shoes, hold the soles in a plane parallel to the plane of the support. A pair of shoes may likewise be supported in the upright position by inserting the heels of the shoes into the sockets at the ends of 60 the loops, c and c^2 .

In the modification shown in Figs. 4 and 5, each support consists of a wire bent into two loops, D, and D'. The inner loop, d, of the wire surrounds a screw b^6 , of the 65 cross bars and the ends of the wire stand adjacent to similar screws. Adjacent to the cross bars the loops have off-sets, d' , and d^2 . The outer sides of the loops have upwardly projecting lugs, d^3 and d^4 .

In use a pair of shoes is supported upon each support, the heels of the shoes abutting against the off-set, d' , d^2 and the soles resting upon the loops, the lugs, d^3 , d^4 , contacting the sides of the shoes.

What I claim is:

1. In a shoe support the combination of a cross-rod, a series of supports, each made of three loops, the side loops having enlarged ends for grasping the heels of shoes, and for forming with the central loop sockets for receiving the tops of inverted shoes, each support engaging the cross-rod.

2. A shoe rack consisting of a series of cross rods, a means of supporting the cross rods, a series of shoe supports engaging the cross rods, each support made of three loops, the side loops having enlarged ends for grasping the heels of the shoes and forming with the central loops sockets for receiving the tops of inverted shoes, the outer wires of each support being bent upwardly into lugs.

SAMUEL HERMANN.
